ATTORNEY.

UNITED STATES PATENT OFFICE.

OSCAR B. FISH, OF ST. GEORGE, NEW YORK.

DESIGN FOR A PEN AND PENCIL HOLDER.

56,349.

Specification for Design.

Patented Oct. 5, 1920.

Application filed February 2, 1920. Serial No. 355,761. Term of patent 7 years.

To all whom it may concern:

Be it known that I, OSCAR B. FISH, a citizen of the United States, and a resident of Castleton Park, St. George, Staten Island, in the county of Richmond and State of New York, whose post-office address is 64 East 11th Street, New York, N. Y., have invented a new, original, and ornamental Design for Pen and Pencil Holders, of which the following is a specification, reference being had to the accompanying drawings, forming a part thereof.

Referring to the drawings:

The figure illustrates the device embodying the design.

I claim:

The ornamental design for a pen and pencil holder as shown.

OSCAR B. FISH.

Witnesses:

ANNA B. FISH,
L. BRINKERHOFF.
